UNITED STATES PATENT OFFICE.

PAUL HOERING, OF BERLIN, AND WILHELM WIELANDT, OF ZWISCHENAHN, GERMANY,

METHOD FOR THE GASIFICATION OF RAW COMBUSTIBLE MATERIALS.

No. 896,912.

Specification of Letters Patent.

Patented Aug. 26, 1908.

Application filed January 27, 1906. Serial No. 298,188.

To all whom it may concern:

Be it known that we, PAUL HOERING, chemist, and a subject of the King of Württemberg, residing at 23 Levetzow street, Berlin, Germany, and WILHELM WIELANDT, chemist, and subject of the Grand Duke of Baden, Germany, residing at Zwischenahn, in the Grand Dukedom of Oldenburg, Germany, have invented certain new and useful Improvements in Methods for the Gasification of Raw Combustible Materials, of which the following is a specification.

This invention relates to a method for gasifying raw combustible materials such as peat and the like bituminous materials containing large quantities of water. Hitherto such bituminous and large quantities of water containing combustible materials were first dried and then brought into a kiln and coked in the latter. The coke was then taken from the kiln and cooled. This cooled coke was then put into a gas generator and gasified. It is clear from this that in this former method at least four apparatus and accordingly four operations were necessary for gasifying peat and the like *i. e.*, drying the wet material in special apparatus, coking the dried material in a coke-oven, taking the hot coke from the oven or kiln and cooling it and at last putting the cooled coke into a gas-generator and gasifying it in the same in order to obtain generator-gas.

The present invention consists essentially therein that materials containing a large percentage of moisture as for example peat are first heated sufficiently to drive off the moisture and other more volatile constituents in order to first dry and coke the material and then partially cooling the coked material by passing through it the steam and gas generated during the coking operation and finally burning the coked material in a gas producer and collecting the products derived from such burning. This method may be modified by passing through the coked material the gases which have been previously driven therefrom in order to cool the material and then placing the coked material in the gas producer and burning the same by admitting to the producer during this operation the previously evolved gases.

We will now first describe the present method in some modifications, reference being had to the accompanying drawings which show some apparatus for carrying out the present method of gasifying peat and the like.

The present method consists essentially in putting the peat or other combustible material containing large quantities (up to 40 or more per cent.) of water into a retort preferably having the shape of a vertical shaft tapering in its lower part and heating this retort in such manner, that the lower part of the retort receives only a little heat.

The heating of the retorts may be effected in any appropriate manner. The inventors prefer however to use gases generated in the retort or in the producer and to heat the retorts by the burning gases from outside so that the peat in the retort is first dried and then coked.

The column of peat or the like loses its water and other volatile constituents which crowd in the upper part of the retort. After a certain time the material which receives the greatest heat is coked and sinks down in the measure as coked material is drawn off in the lower part of the retort and new wet material is put into the retort in its upper part. The steam and other volatile constituents which flow to the upper part of the retort in consequence of the difference in pressure in the upper and lower parts are forced down in a channel or pipe which leads from the upper part of the retort to the lower part which is filled with coke and which lies below the part that receives the greatest heat. The steam and other volatile constituents which are forced down are relatively cool and so effect a cooling of the hot coke in the lower part of the retort. These volatile constituents then flow through the hottest part of the peat-column and are there decomposed and formed to a combustible gas which is sucked off. The cooled coke, which is in the lower part of the retort is periodically dropped into a generator that is arranged just below the retort and in communication with the same. It is essential that the coke in this way is effected not to pass out of the retort into the generator in an incandescent or too hot state, in which case a separating slide or valve, which is arranged between the retort and the generator would have to withstand high temperatures, but that the coke partially or wholly freed from the gases and volatile constituents should be cooled down before passing through the connecting passage to the generator, whereby complete use is made of the heat thus liberated for the process. This may be attained in different ways.

Firstly, the large quantities of steam generated in the upper part of the retort in the upper or drying zone may be as already mentioned compelled in the first place to descend 5 into the lowest part of the retort, to blow through and to cool the partially gas-free coke and then to pass out of the retort together with the remaining gases freed by distillation. This may be effected by arranging

10 a connecting-pipe or conduit open at both ends, or a chamber between the uppermost and lowest parts of the retort and arranging the gas delivery opening in the coking zone of the retort below its center. On account 15 of the natural pressure conditions, the steam developed in the drying-zone is then caused to pass through the connecting-conduit and through the coke to be cooled to the gas-exhaust opening.

20 Secondly, the cooling down of the coke freed from gas may be effected or aided by means of cooling the bottom or lower part of the retort from outside by means of air and water, by either the conically or cylindrically 25 formed coke-holder being cooled outwardly by the necessary combustion air for the heating of the retort or a water-jacket acting as an evaporator being placed round the same, the steam of which may be conducted into 30 the generator being placed below it or below its grate respectively, or directly into the retort.

Thirdly, the separating slide or valve may be provided with suitable water cooling devices and thereby preserved from heating too high.

In this arrangement of the retort, distillation and complete gasification, apart from the separating valves being periodically 40 opened, can, in the first place, be carried on separately. By means of this apparatus the generator may be worked by an injector, an exhauster or a suction-gas-motor; or the distilled gases may be sent by exhausters or 45 the like out of the retort into the condensing apparatus and be used for heating the retort after separating the valuable by-products; or the gases in crude state containing tar and water may be entirely or partly burned. The 50 combination of the retort and the generator may be made such that the gases formed in the generator are led around the retort heating the latter by its own heat alone and itself being thereby cooled and flowing into the 55 purifying apparatus. Or a part of the generator gases purified or not may be brought for burning in the furnace of the retort. The distilled gases and the generator gases may be mixed together before or after their purifying or condensation.

Particularly the tar-containing crude-gases being led through the glowing coked material within the distiller may be sucked off directly into the generator, or they may be 65 burned in the furnace and the smoke-gases be

eventually reduced to pure generator gas. A method of that kind has the superiority that these gases' heat taken up from the coked material is not lost but used for the gasifying process. One single suction-device 70 then suffices and a generator-gas as the only product is generated which is absolutely free from tar.

The generator gases are formed in the known manner by burning the coked material in a tightly closed room the bottom of which consists of a grate through which air is sucked or pressed into the burning combustible material.

The accompanying drawings illustrate different possible ways of making apparatus in accordance with and suitable for carrying out my invention in which:

Figures 1, 2 and 3, 4, 5, 6, and 7 are vertical sections of different forms of apparatus. 80 Fig. 3^a is a horizontal section near the top of Fig. 3.

Similar letters of reference refer to similar parts in all views.

a is a generator, *b* a distiller or retort, 90 which is connected to the generator by a channel or the like, in which a valve *d* is inclosed.

c is a hopper.

In Figs. 1 and 3, *c* are walls arranged with-in the retort and in any distance from the walls of the retort, so that a free room channel *f* remains between both walls. These rooms *f* present conduits by which the gases from the upper part to the lower part of the 100 distiller can be sucked off through waste-pipes *g*. A pipe *h* with a valve can be connected to the upper part of the retort and serves for leading directly the gases vapors and steam out of the retort. Fig. 2 shows 110 openings *i* in the walls of the distiller by which the interior of the distiller *b* is connected to the fire-tubes surrounding the distiller. *k* are channels surrounding the lower 120 part and being connected to the fire-tubes of the distiller. Through these channels air is led into the fire-tubes of the distiller, whereby the air cools the lower walls of the distiller and whereby itself is heated.

Figs. 5 and 6 show a water-jacket *l* surrounding the lower part of the distiller. In Fig. 5 two valves *d*¹ and *d*² separate the distiller *b* from the generator *a*. This water-jacket according to Fig. 5 is connected to pipes *m* and *n*. The pipe *m* leads below the 125 grate of the generator, while the pipe *n* is connected to the interior of the distiller. In these pipes regulating-devices can be inclosed; but these devices are not shown in the drawings.

Relating to Fig. 6, the water-jacket *l* is covered by two walls which inclose channels *q* through, which the vaporized water from the jacket enters the distiller and the hot coked material, through which this water 130

steam is sucked into the waste - pipe f^1 . Gases and tar-vapors generated in the middle zone of the distiller are also drawn from above into the pipe f^1 . The upper part of 5 the distiller is provided with pipes w being arranged behind walls x and having the purpose to let out the steam collecting in the upper part of the retort.

Fig. 7 shows a further form of construction of the apparatus in which a chamber-tap p is arranged between the distiller b and the generator a . This tap is surrounded by a water-cooled jacket p^1 and itself also is suitably cooled with water. A tight fitting joint is 15 thereby obtained and the coke is further cooled before it arrives in the generator. Instead of this any valve with water-cooling may be inserted.

Figs. 1, 2, 3 and 4 show a conduit r arranged in the axis of the distiller room. This conduit may be formed like a pipe or like a chamber opened at both ends and reaching from above to the cooled part of the distiller. A valve or valves may be arranged at the upper 25 per openings of the conduit r being apt for regulating the openings. This conduit conducts the steam vapors and gases from above to below into the cooled zone of the distiller.

Figs. 5 and 6 do not show such a conduit in 30 the axis of the distiller. In the form of the present invention shown in Fig. 5 all the gases vapors and steam generated in the distiller are drawn away together, but in the arrangement shown in Fig. 6 the vapors and 35 steam from the upper colder zone are sucked away separate from the gases preceded in the lower part of the distiller.

Different means of heating the distiller b are shown in the figures. In Figs. 1 and 6 40 the fire-tubes are not shown but are arranged only behind the opposite walls being not cut in the figures. In the arrangements shown in Figs. 2, 4 and 5 the gases distilled in the retort b are used by burning them with air in 45 the fire-tubes of the distiller.

Fig. 3 shows an arrangement to heat the distiller by the heat contained in the gases generated in the generator a . For this purpose the hot gases generated in the gas generator a leave the latter through a channel that touches the retort so that a part of the heat of the generator gases is transferred to the retort.

In the arrangement of Figs. 4 and 7 the 55 fire-tubes of the distiller are connected to the generator by a pipe leading the combustion-gases from the fire-tubes into the generator. These fire-tubes are further connected by a pipe h to the upper zone of the distiller. A valve h^2 allows conducting vapors and gases

from this part of the distiller to the fire-tubes and burning them therein. A valve h allows to regulate the quantity of vapors and gases sucked off and not led into the fire-tubes of the distiller.

As is shown in the illustration presented in Fig. 7, the distiller is connected by a pipe g to a condenser not shown in the figure. From this condenser a pipe g^1 leads back to the fire-tubes of the distiller for the purpose of combustion. These fire-tubes are provided with a waste-pipe t being connected to the generator-room and inclosing a valve u for regulating the quantities of smoke-gases passing from the fire-tubes to the generator a . For 75 the case in which the distilled gases do not suffice for a sufficient heating of the distiller retort, a branch conduit or pipe g^2 is led from the generator-gas-conduit to the conduit g^1 which passes the generator-gas into the fire-tubes.

Having thus described our invention what we claim and desire to secure by Letters Patent is:

1. The herein described method of treating peat and similar materials containing a large percentage of moisture, which consists, first in heating the material sufficiently to drive off the moisture and other more volatile constituents in order to coke the material, then partially cooling the said material by passing through it the steam and gas generated during the coking operation, and finally burning the coked material in a gas generator and collecting the products derived from such burning.

2. The herein described process or method of treating peat and similar materials containing a large proportion of moisture, which consists, first, in sufficiently heating the material to drive off the moisture and other volatile constituents in order to coke the material, then passing through the material which has been coked, the gases which have been previously driven therefrom in order to cool the said material, then placing said coked material in a gas generator and burning the same and during said burning admitting to the generator the previously evolved gases.

In testimony whereof we have hereunto set our hands in presence of two subscribing witnesses.
